Filed May 11, 1960, Ser. No. 60,538

Term of patent 14 years

(Cl. D26—14)

FIG. 1

FIG. 3

FIG. 2

FIG. 1 is a perspective view of a telephone handset showing my new design;

FIG. 2 is a side view of the telephone handset positioned for use on a horizontal surface, the opposite side being substantially a mirror image thereof; and

FIG. 3 is an end view of the telephone handset taken from the left of FIG. 2.

The essential features of the new design reside in the portions shown in full lines.

I claim:

The ornamental design for a telephone handset, substantially as shown and described.
